UNITED STATES PATENT OFFICE.

SIMON BOLLINGER, OF SOUTH WHITLEY, INDIANA.

FLUE STOPPER.

Application filed September 5, 1924. Serial No. 736,067.

To all whom it may concern:

Be it known that I, SIMON BOLLINGER, a citizen of the United States, residing at South Whitley, in the county of Whitley and 5 State of Indiana, have invented certain new and useful Improvements in Flue Stoppers, of which the following is a specification.

This invention relates to new and useful improvements in flue stoppers and more particularly to an improvement on my former 10 Patent #1,503,630 issued August 5, 1924.

The principal object of my invention is to provide a device of this character which may be effectively and securely applied to a stove 15 pipe opening of any diameter in chimneys.

A further object of the invention is to provide a device of this character which when secured in place will remain therein and effectively carry out the purposes for which 20 the same is designed without danger of casual displacement and further without permitting the escape of soot, gases, etc.

Still another object resides in providing an improved retaining means which is capable 25 of adjustment for accommodation to use in connection with flue openings of various diameters.

A further object resides in providing a device which may be knocked down and 30 nested for shipment, which may be quickly and readily assembled, and one which is simple and durable in construction, inexpensive to manufacture, and very efficient in use.

With these and other objects in view, my 35 invention consists in the novel features of construction, combination and arrangement of parts, as will be hereinafter referred to and more particularly pointed out in the 40 specification and claims.

In the accompanying drawing forming a part of this application—

Figure 1 is a vertical section through the 45 invention applied to use;

Figure 2 is a plan view of the stopper removed;

Figure 3 is a transverse section therethrough;

Figure 4 is a vertical section as seen on the 50 line 4—4 of Fig. 1.

In describing the invention I shall refer to the drawing in which similar reference characters designate corresponding parts throughout the several views, and in which 55 1 designates a flue opening formed in a

structure 2 of any character whatsoever. It will be understood that this flue opening may be of any desired diameter as my invention is designed to cover the end of said opening and is so constructed that it may be adjusted 60 for flue openings of various diameters.

My invention comprises a disk-like plate 3 of the usual or any preferred diameter having a central opening therein, the greater portion of which is crowned or arched and 65 the outer portion 4 of which forms substantially an annular flange thereon. This outer annular flange portion 4 is provided with a plurality of annular grooves 5 which obviously provide rigidity and strength. 70 These grooves 5 also provide flat annular spaces therebetween which are adapted to contact with the end edges of flue openings of various diameters. Being flat, these 75 spaces will contact snugly against the peripheral edge of the flue opening and thus prevent dust, soot and gases from escaping therefrom.

This plate 3 actually forms the stopper in itself but, of course, some retaining means 80 must be provided to keep the same in place. The principal features of my invention reside in this improved retaining means which will be hereinafter and more specifically described.

To this end I provide a spring metal strip 85 6 having a central opening whereby a bolt 7 may extend therethrough as well as through the opening in the plate 3 to centrally secure said strip to said plate. This strip is 90 constructed of suitable spring metal of a required length and breadth and adjacent its ends the inner face thereof is slightly grooved, as shown at 8, for a purpose to be hereinafter described.

This spring metal strip 6 is bent arcuately so that its ends are disposed away from the plate 3 and applied to the bolt 7 is an egg-shaped loop member 9, said member being constructed of a single strand of wire. The 100 single strand of wire is looped and its ends overlapped in spaced relation and the extreme free ends of said wire loosely lapped, as shown at 10, over the opposed overlapping end portion. Thus a loop member is provided which is obviously capable of adjustment by contraction or expansion, and as this loop member forms an essential feature of the retaining means for my flue stopper, it is obvious that adjustment will be made 105 110

thereof according to the diameter of the flue opening to which the device is to be applied.

The overlapping end portions of the loop member being spaced enable the spaced portions to straddle the bolt 7 on the strip 6 and applied on the bolt over the loop member at this point is a clamping plate or washer 11. A nut 12 applied to the threaded end of the bolt 7 holds the elements in place on the inner face of the plate 3.

The end portions of the metal strip 6 are adapted to contact with the side portions of the loop member 9 when the device is applied to use and it is obvious that the grooves 8 in said strip will receive the sides of the loop therein. The wire loop member 9 is calculated to force the ends of the metal strip outwardly for firm engagement with the inner walls of the flue opening, the sides of the loop resting or engaging the grooves 8. The metal strip 6, which forms part of the retaining means, is designed to give greater friction to the device as it has considerable surface with which to engage the walls of the flue opening.

In assembling the flue stopper the bolt 7 is put in place in the center of the disk-like plate 3. The metal strip 6 is then applied over the bolt to the inner face of the plate and the wire loop member 9 is then applied to the bolt so that the overlapping portions straddle said bolt. Then the washer or clamping plate 11 is applied to the bolt. The wire loop member is then compressed or expanded to suit the size of the flue opening to which the device is to be applied and the nut 12 is then turned home on the bolt to secure the elements to the plate 3. The ends of the metal strip 6 are then bent against the sides of the wire loop member 9 and the flue stopper is then ready for use.

From the foregoing description of the construction of my improved device, the operation will be readily understood, and it will be seen that I have provided a simple, inexpensive and efficient means for carrying out the objects of the invention.

While I have particularly described the elements best adapted to perform the functions set forth, it is obvious that various changes in form, proportion, and in the minor details of construction may be resorted to, without departing from the spirit or sacrificing any of the principles of the invention.

Having thus described my invention, what I claim is:

1. In a flue stopper, a plate, a spring metal arcuate strip applied to the inner face thereof, said strip having grooves formed on the inner face of the same adjacent its ends, a resilient loop member applied to the plate within said arcuate strip and capable of contraction and expansion, the sides of said loop member being adapted to contact with the grooves in said strip, and means for removably securing said loop member, strip and plate together centrally.

2. In a flue stopper, a plate, an arcuate spring metal strip applied to the inner face thereof, a loop member formed of a single strand of wire having its end portions arranged in spaced overlapping relation, the extreme free ends of said wire being loosely lapped over the opposed end portion of the wire to permit of contraction and expansion of said loop member, and means for securing said loop member, strip and plate together centrally.

3. In a flue stopper, a plate, a bolt extending centrally therethrough, an arcuate spring metal strip applied on said bolt to the inner face of said plate, a resilient loop member formed of a single strand of wire having its end portions arranged in overlapping relation and straddling said bolt on the inner face of said strip, the extreme free ends of said wire being loosely lapped over the opposed end portion of the wire to permit of contraction and expansion of said loop, a clamping plate applied to the bolt over the spaced portions of said wire, and a nut applied to the end of said bolt, as and for the purposes described.

In testimony whereof I affix my signature.
SIMON BOLLINGER.
